UNITED STATES PATENT OFFICE

ROBERT C. SPENCER, OF OAK PARK, ILLINOIS, ASSIGNOR TO CASEMENT HARDWARE CO., OF CHICAGO, ILLINOIS, A CORPORATION OF ILLINOIS

CLOSURE FASTENER

Application filed November 18, 1927. Serial No. 234,103.

The present invention relates to closure fasteners and is more particularly concerned with closure fasteners adapted to insure the complete closing of the closure by a single operator located at any convenient point.

In the use of casement windows, doors and other closures it is frequently found that the closure becomes warped after a period of use so that, although one part of a closure may be closed, the closure may be so warped that another edge may remain partially open, admitting cold air or rain, and presenting a crack which may facilitate the entrance of a jemmy or other breaking tool. It is also desirable to provide automatic means for securing the closure in a plurality of remote points, thereby rendering warping impossible by securing the closure in flat position and also guarding against unauthorized entrance from the outside.

One of the objects of my invention is the provision of automatic mechanism for insuring a complete closing of casement windows and the like about the whole of the outer edge of the closure, and for automatically securing the closure at a point remote from the usual operator or fastener, by merely closing and fastening the window with the usual fastener.

Another object is the provision of a closure fastener for casement windows, doors or the like, which is actuated by the closing movement of a closure member to draw in the free corners of the member, and which embodies a minimum of moving parts capable of permitting any lost motion.

Another object is the provision of a closure fastener of the class described, including a torsion shaft carrying fixed members for engagement with adjacent parts, thereby eliminating the lost motion by the use of a plurality of members pivoted to each other, and providing a resilient mechanism which may be adjusted to take up any amount of warp in the window.

Another object of my invention is the provision of closing or securing means for casement windows and the like comprising a mechanism to be acted upon by one part of a closure during a closing movement for exert-

ing a closing force on another remote part of the closure.

Another object of my invention is the provision of automatic securing means for one part of a casement window or the like which is both actuated by the closing movement of the closure to secure the same and which is automatically released by the opening movement of the closure.

Another object of my invention is the provision of a closure operator and fastener of the class described which may be used on right-hand or left-hand closures, single or double closures, and which is adaptable to be used with any size of closure by the use of stock parts which may be cut to size on the job with ordinary tools.

Other objects and advantages of my invention will appear more fully from the following description and from the accompanying drawing, in which similar characters of reference indicate similar parts throughout the several views:

In the drawings, Figure 1 is an elevational view of a double casement window equipped with my closure fastener and a geared operator;

Figure 2 is a cross-sectional plan view of the same taken on the line 2-2 of Figure 1;

Figure 3 is an elevational view of a modified form of my closure fastener applied to a steel window;

Figure 4 is a cross-sectional plan view taken on line 4-4 of Figure 3;

Figure 5 is an enlarged detailed cross-sectional view of the mechanism of Figure 4, shown in the position when the window is open;

Figure 6 is an elevational view in partial cross-section of the fastening bolt employed in Figure 3; and

Figure 7 is a plan view of the keeper employed with the bolt shown in Figures 3 and 6.

Referring to Figures 1 and 2, 10 indicates in its entirety a conventional window frame or support which may be provided with the usual window stop 11, screen 12 and casement window 13. The casement window may be supported on the window frame by the usual hinges 14, and it may also be provided with

any convenient form of operator for opening and closing the window.

In the present embodiment I have shown a geared operator which may be exactly as described in the prior application, Serial No. 5 185,982, of Charles E. Spencer and Owen W. Roberts, for casement window operators, filed April 23, 1927, which issued as Patent No. 10 1,744,341 on January 21, 1930. This operator 15 consists essentially of the supporting housing 15, adapted to be secured to the window sill 16 by a plurality of screws 17 and containing a worm 18, rotatably supported to actuate a worm gear 19 secured to an arm 20. 20 The arm 20 carries a slider 21 in its end which is adapted to slide in a guide 22 and when the worm 18 is actuated by means of the handle 23, the arm 20 is adapted to move the slider 21 in its guide 22 to open or close the window.

I do not wish to limit myself to any form of operator, however, as my closure fastener may be employed with many forms of operators.

25 My invention is of particular importance, however, with an operator which is adapted to act upon and secure only one edge of the casement window, the closure fastener serving to insure the closure of other edges and 30 to secure them.

In the embodiment shown in Figures 1 and 2, the closure fastener may include a shaft 24 rotatably supported by the closure and preferably located adjacent the edge which has 35 the greatest range of movement, since the complete closure of this edge will insure closing all around the window.

The shaft 24 may be carried by a pair of brackets 25 and 26 of sheet metal bent to form bearings for said shaft and having outwardly extending flanges 27, for attachment to the window or other support.

40 The shaft 24 may be provided at one end with a cam 28 which is preferably symmetrically formed upon both sides as at 29 so that it is adapted to be used on right-hand or left-hand windows.

The cam 28 is formed with a hub 31 which may be secured to the shaft 24 either by providing a non-circular end on said shaft in a 45 complementary aperture or by a set screw 32. The set screw has the advantage of permitting adjustment of the cam to insure complete closing under any condition of installation, 50 but it is also possible to so locate the brackets or shoulders against which the cam acts so that no adjustment is required.

The shaft 24 constitutes a torsion rod or member which is placed under torsional 55 strain when the lower edge of the window is brought into engagement with the cam 28 and the upper arm 33 engages shoulder 46 to pull the free edge of the window shut.

The provision of such a torsional member enables me to do away with pivoted joints in

the mechanism, thereby eliminating any possible chance of lost motion, and the resilient mechanism provided thereby may be adjusted to take up any amount of warp in a window or the like.

70 The shaft 24 is also provided with a closing arm 33 consisting of a lever having a hub 34 provided with a bore 35, adapted to receive the shaft 24, to which it may be affixed in the same manner as described for the cam 28. The bore 35 may be counterbored, as at 75 36, and the walls of said counterbore may be cut away as at 37 to permit access to a spring 38.

75 The spring 38 may consist of a helical spring adapted to be received in the counterbore 36 about the shaft 24, and having one end secured in the slot 39 in the arm 33, and the other end extending from the counterbore in the cut-out 37 to engage the window 80 or other fixed part. The spring 38 is, therefore, adapted to bias the shaft 24 with its cam 28 and arm 33 in a clockwise direction in Figure 2, rotation of the shaft being limited by a stop 40, consisting of a pin projecting from 85 either hub and engaging the window or other fixed part. The cam and arm are shown in this limiting position in dotted lines in Figure 2. It should also be noted that the hubs 34 and 31 engaging the brackets 26 and 25, respectively, are adapted to prevent the axial movement of the shaft 24 and support the same.

90 The closure support is also provided with a pair of shoulders or brackets consisting of a bracket 41, adapted to engage the cam 29, and a bracket 42 adapted to engage the arm 33. These brackets may consist of sheet metal members having an attaching flange 43 secured to the closure support by a plurality of screws 44, and having an upwardly extending flange 45 at substantially right angles to the attaching flange 43. The bracket 42, 95

100 which may be of similar structure, is attached to the closure support, in the present instance, at the top of the window frame with 105 the flange 46 projecting downward in position to be engaged by the arm 33. The arm 33 should engage on the opposite side of the flange 46 from the window 13, in such manner that counter-clockwise rotation of the 110 shaft 24 in Figure 2 will cause the arm 33 to engage the fixed flange 46 and react against said arm to pull the upper edge of the window shut. The bracket 41 is preferably carried by the closure support at the sill of the 115 window frame in position to be engaged by the cam 28, and the location of the flange 45 should be such that when the lower edge of the window is completely closed and the cam 28 is engaging the flange 45, the arm 33 has 120 engaged the flange 46 and firmly pulled the upper edge of the window into closed position.

125 The shape of the cam 29 may be made such that friction is greatly reduced by a single point contact between the cam and 130

flange and, if desired, both the cam and arm 33 might be provided with anti-friction rollers. The cam may also be shaped to materially increase the closing force at the limit of its movement by varying the moment arm at which the cam engages. The operation of this embodiment is as follows:

When the window is in the dotted line position shown in Figure 2, the cam 28 and arm 33 have assumed the position shown in dotted lines, being moved to this position by the spring 36 until the stop 40 engages the window. When the window is closed by rotating the crank 23, the arm 20 will cause the slider 21 to pull the window shut, sliding in the guide 22, and the lower edge of the window may be tightly closed by the operator.

As the screw type of operator is not reversible the arm 20 will be held in adjusted position by engagement of the worm gear 19 of the screw 18.

During the closing movement of the window the cam 28 is engaged by the flange 45 along which the cam slides rotating the shaft 24 in a counter-clockwise direction. The relation of the parts is such that the arm 33 rotates into position behind the flange 46 and engages said flange, so that if the window 13 is warped the continued rotation of the shaft 24 causes the arm 33 to react against the flange 46 and pull the upper edge of the window into complete closure. When the window is closed the parts are in the position shown in Figure 2, the lower edge of the window being secured by means of the screw type operator, while the upper edge of the window is secured by engagement of the arm 33 behind the flange 46, reacting against the window which reacts through the shaft 24 against the bracket 41.

It should also be noted that the companion window 47 may be operated by a similar screw operator which will be adapted to firmly close and secure its lower edge, while the upper edge of this window will also be secured by my closure fastener, since the window 47 may be rabbetted, as at 48, to engage behind the window 13. The upper edge of the window 13 secured by my closure fastener also secures the upper edge of the companion window 47.

In the embodiment shown in Figures 3 to 7 my closure fastener is illustrated with a steel window and, although the shaft is mounted upon the closure support, the shoulders being carried by the window, this is a substantial reversal of the preceding embodiment, and the principle of operation is substantially the same. In this embodiment the window frame may also be indicated in its entirety by the numeral 10, the movable closure being designated by 48. The supporting frame 10 is preferably formed of Z-bars 49, while the window frame may be formed of similar bars

supported for pivotal movement by the hinges 50.

In this embodiment the structure of the cam 28, shaft 24 and arm 33 may be substantially the same, but this shaft is supported by a pair of brackets 51 and 52 carried by the fixed frame. Bracket 51 may consist of a flat piece of metal having a bore to receive the shaft 24, said bracket being riveted or otherwise secured to the sill. The bracket 52 may consist of a flat piece of sheet metal likewise secured to the upper side of the fixed frame and having a laterally bent flange 53 with a bore to form a bearing for the shaft 24.

The cam 28 in Figure 3 may be engaged directly by the lower edge of the casement window, while the upper edge of the window may be provided with a bracket or shoulder 54 riveted or spot-welded to the same and consisting of a sheet metal member having an attaching flange 55 and off-set 56 and an engaging flange 57 substantially parallel to the window. In this embodiment the arm 33 is adapted to engage between the window and the flange 57 to pull the upper edge of the window into closed position.

The shaft is likewise provided with a spring 38 engaging the edge of the fixed frame at one end and having its other end secured in a slot 39 in the arm 33. The spring 38 biases the shaft and arms in a counter-clockwise direction to the position shown in Figure 5, such movement being limited by engagement of the cam or arm with the edge of the fixed frame at 55a.

As previously described my closure fastener may be employed with any type of operator which will firmly close one edge of the window, preferably the lower edge, for the purpose of conveniently locating the operator. Where a casement window has been warped it is necessary to apply considerable force in the closing movement and I prefer to employ a fastener of the type shown in my prior application, Serial No. 88,234, filed February 15, 1926, for casement window fasteners. This fastener, which is adapted to cam the lower edge of the casement window shut, consists essentially of a bracket 56 for rotatably and slidably supporting a bolt 57a, having a handle 58, and a lower end with a flat side 59. The end may also be beveled as at 60 and it is adapted to be inserted in a keeper 61, having an aperture 62 with a flat side 63.

The exact details of such a fastener may be varied provided it is adapted to exert sufficient force to close the window at the lower edge and also correct any warping.

The operation of this embodiment is as follows:

When the window 48 is closed its lower edge engages the cam 28, rotating the cam 28, shaft 24 and arm 33 in a counter-clockwise

direction. As the closing movement progresses the relation of the parts is such that the arm 33 rotates in behind the flange 57 and when the lower edge of the window has been moved to closed position, the upper edge is also forced to such position by engagement of the arm 33 behind the flange 57. My closure fastener not only forces the remote upper edge of the window into closed position, but secures it in such position as long as the window is secured by the bolt 57a.

While I have illustrated my device with a spring to bias it to the position shown in Figure 5, many of the advantages of my fastener may be realized without employing a spring, since it will be noted that when the window 48 is opened from the position in Figure 4, the flange 57 will naturally force the arm 33 counter-clockwise, moving the cam 20 and arm to the position shown in Figure 5. When the parts are in this position they are already disposed so that the arm 33 will automatically enter behind the flange 57 when the window is closed and it will be evident that the device will operate without employing a spring. On the other hand the spring insures the location of the mechanism in proper position at all times and is therefore included in the preferred embodiment.

It should also be noted that the finger 33 is preferably made of greater length than the cam 28 in order that the end of the finger may have a wider range of movement during the same time that the cam moves. Thus the finger moves farther than the cam and is adapted to take up any lag caused by the warping of the window.

It should also be noted that where a fastening bolt, such as is used in Figure 6, is employed on a steel window, the keeper 61 may be eliminated and the end 59 of the bolt may react directly against the flange which forms the lower edge of the window frame.

It will thus be observed that I have invented a closure fastener which automatically secures the upper or remote edge of the window when the lower edge is closed and which is adapted to prevent any warping of the window or unauthorized opening from the upper edge. It should also be noted that my invention may be applied to left-hand and right-hand windows or to single or double windows or other types of closures, and it may readily be used with any size of window since the shaft 24 may be constructed of sheet metal pipe which may be cut to the proper length by an ordinary hacksaw on the job.

My closure fastener is actuated by a part of the same window on which the fastener itself reacts, and the simple and effective structure described is capable of long service without deterioration or necessity for adjustment. The torsion shaft makes the entire mechanism resilient and the fixed arms or fingers carried

by the shaft may be adjusted so as to satisfactorily close and secure any window or other closure.

While I have illustrated and described a specific embodiment of my invention, many modifications may be made without departing from the spirit of the invention, and I do not wish to be limited to the precise details of construction set forth, but desire to avail myself of all changes within the scope of the appended claims.

Having thus described my invention, what I claim is new and desire to secure by Letters Patent of the United States is:

1. In a closure fastener the combination of a supporting member with a movable closure member, bearing brackets carried by one of said members, a shaft rotatably supported in said brackets, a cam carried by said shaft, an arm carried by said shaft, a shoulder carried by said support for engagement with said cam and spring means carried by said shaft for biasing said arm into position to enter behind said second shoulder.

2. In a closure fastener, the combination of a rotatable torsion member with a pair of radially projecting members, one of said radially projecting members being adapted to be engaged by one part of a closure member and the other of said radially projecting members being adapted to serve as a closure fastener for another part of the same closure member.

3. In a closure fastener, the combination of a pair of supporting bearings with a torsion rod, fingers fixed at spaced points on said torsion rod, and shoulders carried by a relatively movable member and engageable on opposite sides of the respective fingers whereby the movement of said member actuates said rod to draw in other parts of said member.

4. The combination of a frame with a pivoted closure for said frame, a pair of brackets carried by said frame, a shaft rotatably mounted on said closure, an arm carried by said shaft engaging inside one of said brackets, and a second arm carried by said shaft engaging outside the other of said brackets.

5. The combination of a frame with a pivoted closure for said frame, a pair of brackets carried by said frame, a shaft rotatably mounted on said closure, an arm carried by said shaft engaging inside one of said brackets, a second arm carried by said shaft engaging outside the other of said brackets, and a spring for biasing said arms away from said closure.

6. In a closure fastener, the combination of a pair of bearing brackets with a torsion rod rotatably mounted in said brackets, a cam having a hub fixed to said torsion rod, a shouldered bracket adapted to engage on one side of said cam, an arm having a hub fixed

to said torsion rod and a shouldered bracket adapted to engage the opposite side of said arm.

5 7. In a closure fastener, the combination of a pair of bearing brackets with a torsion rod rotatably mounted in said brackets, a cam having a hub fixed to said torsion rod, a shouldered bracket adapted to engage on one side of said cam, an arm having a hub fixed to said torsion rod and a shouldered bracket adapted to engage the opposite side of said arm.

10 10 said hubs being adapted to serve as thrust bearings in connection with said bearing brackets.

15 8. In a closure fastener, the combination of a pair of bearing brackets with a torsion rod rotatably mounted in said brackets, a cam having a hub fixed to said torsion rod, a shouldered bracket adapted to engage on one side of said cam, an arm having a hub fixed to said torsion rod, a shouldered bracket adapted to engage the opposite side of said arm, and a spring for biasing said arm into position to engage behind said latter shouldered bracket.

20

25 In witness whereof, I hereunto subscribe my name this 14th day of November, A. D. 1927.

ROBERT C. SPENCER.
